UNITED STATES PATENT OFFICE.

EDWIN HUTCHINGS, OF HARTFORD, CONNECTICUT.

IMPROVEMENT IN PRINTERS' GALLEYS.

Specification forming part of Letters Patent No. **88,041**, dated March 23, 1869.

To all whom it may concern:

Be it known that I, EDWIN HUTCHINGS, of Hartford, in the county of Hartford and State of Connecticut, have invented a new and Improved Printers' Galley; and I do hereby declare that the following is a full, clear, and exact description thereof, which will enable others skilled in the art to make and use the same, reference being had to the accompanying drawings forming part of this specification.

This invention relates to improvements in printers' galleys; and consists in providing a rest for the same, whereby the bottom thereof will be presented to and maintained in the same plane with the top of the table to receive the type, as will be more fully described on reference to the accompanying drawings, wherein—

Figure 1 represents a plan view of my improved galley, and Fig. 2 represents a transverse section of the same.

Similar letters of reference indicate corresponding parts.

A represents the bottom of the galley, and B the sides thereof. The said sides, at the end of the galley which receives the type, are

made to project beyond the bottom, as represented at C, whereby, when the bottom is presented to the edge of the stone or table to receive the type, the said ends will rest on the top thereof, and the said bottom be maintained in exactly the same plane with the edge of the table, insuring the sliding of the type thereon without disarranging them, and avoiding the expensive arrangement of a rabbet on the table.

Hitherto the assistance of a second man has been required to slide a page of type from an ordinary stone or table onto a galley to prevent making pi. This invention enables one man alone to do the same with more ease and with greater safety.

Having thus described my invention, I claim as new and desire to secure by Letters Patent—

Printers' galleys, provided with rests C to bear upon the tops of the tables when receiving the type, substantially as specified.

EDWIN HUTCHINGS.
